(57) **ABSTRACT**

Provided is a drive compensation circuit including a first register unit, a second register unit, a selection unit, a voltage level shifter, a digital-to-analog conversion unit, and an amplification unit. The first register unit and the second register unit are respectively connected to the selection unit. The selection unit, the voltage level shifter, the digital-to-analog conversion unit, and the amplification unit are connected in sequence.

DRIVE COMPENSATION CIRCUIT AND DATA DRIVE DEVICE

CROSS-REFERENCE TO RELATED APPLICATIONS

This is the U.S. National Stage of International Patent Application No. PCT/CN2017/111259, filed Nov. 16, 2017, which in turn claims the benefit of Chinese Patent Application No. 201711009010.1, filed Oct. 25, 2017.

BACKGROUND

Field

The present disclosure relates to a technological field of liquid crystal displays, and more particularly to a drive compensation circuit and a data drive device.

Background

Please refer to FIG. 1. FIG. 1 illustrates a drive compensation circuit in the prior art. When one data drive voltage is provided for one data line, two different data voltages are required for a transistor T1 to compensate a threshold voltage V_{th} of the transistor T1. A frequency of a MINI LVDS of a conventional data drive chip is lower. A compensation method is to decrease a frame rate and then to provide a MINI CLK, thereby compensating the V_{th} of the transistor T1. However, the method cannot meet the demand for mass production.

Consequently, defects exists in the prior art and urgently need to be improved.

SUMMARY OF THE DISCLOSURE

An objective of the present disclosure is to provide a drive compensation circuit and a data drive device having a beneficial effect of effectively compensating a drive voltage of a data drive unit.

To solve the above-mentioned problem, technical schemes provided by the present disclosure are as follows.

The present disclosure provides a drive compensation circuit including a first register unit, a second register unit, a selection unit, a voltage level shifter, a digital-to-analog conversion unit, and an amplification unit.

The first register unit and the second register unit are respectively connected to the selection unit. The selection unit, the voltage level shifter, the digital-to-analog conversion unit, and the amplification unit are connected in sequence.

The first register unit is configured to acquire and store a first compensation signal.

The second register unit is configured to acquire and store a second compensation signal.

The selection unit is configured to selectively connect the first register unit or the second register unit to the voltage level shifter. The voltage level shifter processes and transmits the first compensation signal or the second compensation signal to the digital-to-analog conversion unit. The digital-to-analog conversion unit converts the processed first compensation signal or the processed second compensation signal to a corresponding analog signal. The amplification unit amplifies the analog signal with a predetermined multiple and then transmits the amplified analog signal to a data drive circuit for compensation. The amplification unit is an analog buffer amplifier. The selection unit is a switch chip.

In the drive compensation circuit of the present disclosure, the first register unit includes a first receiver, a first shift register, and a first data register. The first receiver, the first shift register, and the first data register are connected in sequence.

In the drive compensation circuit of the present disclosure, the second register unit includes a second receiver, a second shift register, and a second data register. The second receiver, the second shift register, and the second data register are connected in sequence.

In the drive compensation circuit of the present disclosure, the first receiver and the second receiver are Mini-LVDS receivers.

The drive compensation circuit of the present disclosure further includes a frame memory. The frame memory stores the first compensation signal and the second compensation signal.

In the drive compensation circuit of the present disclosure, the first data register has a first control port configured to access a first control signal STB1, the second data register has a second control port configured to access a second control signal STB2, and the selection unit has a third control port configured to access a third control signal DS.

When the third control signal DS is at a low level, the first compensation signal in the frame memory is read and stored in the first shift register. When the first control signal STB1 is at a rising edge, the first compensation signal is outputted to the first data register.

When the third control signal DS is at a high level and the first control signal STB1 is at a falling edge, the first compensation signal in the first data register is transmitted to data lines after being processed by the voltage level shifter, the digital-to-analog conversion unit, and the amplification unit.

When the second control signal STB2 is at a rising edge, the second compensation signal is stored in the second data register. When the third control signal DS is at a low level and the second control signal STB2 is at a falling edge, the second compensation is transmitted to the data lines.

The present disclosure further provides a drive compensation circuit including a first register unit, a second register unit, a selection unit, a voltage level shifter, a digital-to-analog conversion unit, and an amplification unit.

The first register unit and the second register unit are respectively connected to the selection unit. The selection unit, the voltage level shifter, the digital-to-analog conversion unit, and the amplification unit are connected in sequence.

The first register unit is configured to acquire and store a first compensation signal.

The second register unit is configured to acquire and store a second compensation signal.

The selection unit is configured to selectively connect the first register unit or the second register unit to the voltage level shifter. The voltage level shifter processes and transmits the first compensation signal or the second compensation signal to the digital-to-analog conversion unit. The digital-to-analog conversion unit converts the processed first compensation signal or the processed second compensation signal to a corresponding analog signal. The amplification unit amplifies the analog signal with a predetermined multiple and then transmits the amplified analog signal to a data drive circuit for compensation.

In the drive compensation circuit of the present disclosure, the first register unit includes a first receiver, a first shift

register, and a first data register. The first receiver, the first shift register, and the first data register are connected in sequence.

In the drive compensation circuit of the present disclosure, the second register unit includes a second receiver, a second shift register, and a second data register. The second receiver, the second shift register, and the second data register are connected in sequence.

In the drive compensation circuit of the present disclosure, the first receiver and the second receiver are Mini-LVDS receivers.

The drive compensation circuit of the present disclosure further includes a frame memory. The frame memory stores the first compensation signal and the second compensation signal.

In the drive compensation circuit of the present disclosure, the first data register has a first control port configured to access a first control signal STB1, the second data register has a second control port configured to access a second control signal STB2, and the selection unit has a third control port configured to access a third control signal DS.

When the third control signal DS is at a low level, the first compensation signal in the frame memory is read and stored in the first shift register. When the first control signal STB1 is at a rising edge, the first compensation signal is outputted to the first data register.

When the third control signal DS is at a high level and the first control signal STB1 is at a falling edge, the first compensation signal in the first data register is transmitted to data lines after being processed by the voltage level shifter, the digital-to-analog conversion unit, and the amplification unit.

When the second control signal STB2 is at a rising edge, the second compensation signal is stored in the second data register. When the third control signal DS is at a low level and the second control signal STB2 is at a falling edge, the second compensation is transmitted to the data lines.

An embodiment of the present disclosure further provides a data drive device including a data drive unit and a drive compensation circuit. The data drive unit and the drive compensation circuit are connected to data lines.

The drive compensation circuit includes a first register unit, a second register unit, a selection unit, a voltage level shifter, a digital-to-analog conversion unit, and an amplification unit.

The first register unit and the second register unit are respectively connected to the selection unit. The selection unit, the voltage level shifter, the digital-to-analog conversion unit, and the amplification unit are connected in sequence.

The first register unit is configured to acquire and store a first compensation signal.

The second register unit is configured to acquire and store a second compensation signal.

The selection unit is configured to selectively connect the first register unit or the second register unit to the voltage level shifter. The voltage level shifter processes and transmits the first compensation signal or the second compensation signal to the digital-to-analog conversion unit. The digital-to-analog conversion unit converts the processed first compensation signal or the processed second compensation signal to a corresponding analog signal. The amplification unit amplifies the analog signal with a predetermined multiple and then transmits the amplified analog signal to a data drive circuit for compensation.

In the data drive device of the present disclosure, the first register unit includes a first receiver, a first shift register, and

a first data register. The first receiver, the first shift register, and the first data register are connected in sequence.

In the data drive device of the present disclosure, the second register unit includes a second receiver, a second shift register, and a second data register. The second receiver, the second shift register, and the second data register are connected in sequence.

In the data drive device of the present disclosure, the first receiver and the second receiver are Mini-LVDS receivers.

The data drive device of the present disclosure further includes a frame memory. The frame memory stores the first compensation signal and the second compensation signal.

In the data drive device of the present disclosure, the first data register has a first control port configured to access a first control signal STB1, the second data register has a second control port configured to access a second control signal STB2, and the selection unit has a third control port configured to access a third control signal DS.

When the third control signal DS is at a low level, the first compensation signal in the frame memory is read and stored in the first shift register. When the first control signal STB1 is at a rising edge, the first compensation signal is outputted to the first data register.

When the third control signal DS is at a high level and the first control signal STB1 is at a falling edge, the first compensation signal in the first data register is transmitted to data lines after being processed by the voltage level shifter, the digital-to-analog conversion unit, and the amplification unit.

When the second control signal STB2 is at a rising edge, the second compensation signal is stored in the second data register. When the third control signal DS is at a low level and the second control signal STB2 is at a falling edge, the second compensation is transmitted to the data lines.

The embodiments of the present disclosure have a beneficial effect of effectively compensating a drive voltage of a data drive unit.

BRIEF DESCRIPTION OF THE DRAWINGS

FIG. 1 illustrates a drive compensation circuit in the prior art.

FIG. 2 illustrates a structural diagram of a drive compensation circuit in accordance with a preferred embodiment of the present disclosure.

FIG. 3 illustrates a detailed circuit diagram of a drive compensation circuit in accordance with a preferred embodiment of the present disclosure.

FIG. 4 illustrates a signal timing diagram in accordance with an embodiment of the present disclosure.

DETAILED DESCRIPTION OF THE PREFERRED EMBODIMENTS

The following embodiments are referring to the accompanying drawings for exemplifying specific implementable embodiments of the present disclosure. Furthermore, directional terms described by the present disclosure, such as upper, lower, front, back, left, right, inner, outer, side, etc., are only directions by referring to the accompanying drawings, and thus the used directional terms are used to describe and understand the present disclosure, but the present disclosure is not limited thereto.

In the drawings, elements with similar structures are labeled with like reference numerals.

Please refer to FIG. 2. FIG. 2 illustrates a structural diagram of a drive compensation circuit in accordance with

a preferred embodiment of the present disclosure. The drive compensation circuit includes a first register unit **10**, a second register unit **20**, a selection unit **30**, a voltage level shifter **40**, a digital-to-analog conversion unit **50**, and an amplification unit **60**. The first register unit **20** and the second register unit **30** are respectively connected to the selection unit **30**. The selection unit **30**, the voltage level shifter **40**, the digital-to-analog conversion unit **50**, and the amplification unit **60** are connected in sequence.

The first register unit **10** is configured to acquire and store a first compensation signal.

The second register unit **20** is configured to acquire and store a second compensation signal.

The selection unit **30** is configured to selectively connect the first register unit **10** or the second register unit **20** to the voltage level shifter **40**. The voltage level shifter **40** processes and transmits the first compensation signal or the second compensation signal to the digital-to-analog conversion unit **50**. The digital-to-analog conversion unit **50** converts the processed first compensation signal or the processed second compensation signal to a corresponding analog signal. The amplification unit **60** amplifies the analog signal with a predetermined multiple and then transmits the amplified analog signal to a data drive circuit for compensation. The data drive circuit outputs compensated drive voltage signals to data lines.

The voltage level shifter **40** is configured to process and transmit the first compensation signal or the second compensation signal to the digital-to-analog conversion unit **50**. For example, a voltage of the first compensation signal or the second compensation signal is 3.3V. The voltage level shifter **40** increases 3.3V to 5V required by the digital-to-analog conversion unit **50**.

The amplification unit **60** is an analog buffer amplifier to enhance output drive ability.

The digital-to-analog conversion unit **50** is a normal miniature digital-to-analog converter.

The selection unit **30** is a switch chip.

Please refer to FIG. 3. The first register unit **10** includes a first receiver **11**, a first shift register **12**, and a first data register **13**. The first receiver **11**, the first shift register **12**, and the first data register **13** are connected in sequence.

The second register unit **20** includes a second receiver **21**, a second shift register **22**, and a second data register **23**. The second receiver **21**, the second shift register **22**, and the second data register **13** are connected in sequence.

The first receiver **11** and the second receiver **21** are Mini-LVDS receivers.

In some embodiments, the drive compensation circuit further includes a frame memory. The frame memory stores the first compensation signal and the second compensation signal.

Further, the first data register **13** has a first control port configured to access a first control signal STB1. The second data register **23** has a second control port configured to access a second control signal STB2. The selection unit **30** has a third control port configured to access a third control signal DS.

When the third control signal DS is at a low level, the first compensation signal in the frame memory is read and stored in the first shift register **12**. When the first control signal STB1 is at a rising edge, the first compensation signal is outputted to the first data register **13**.

When the third control signal DS is at a high level and the first control signal STB1 is at a falling edge, the first compensation signal in the first data register **13** is transmit-

ted to the data lines after being processed by the voltage level shifter **40**, the digital-to-analog conversion unit **50**, and the amplification unit **60**.

When the second control signal STB2 is at a rising edge, the second compensation signal is stored in the second data register **23**. When the third control signal DS is at a low level and the second control signal STB2 is at a falling edge, the second compensation is transmitted to the data lines.

In the present embodiment, the first control signal STB1, the second control signal STB2, and the third control signal DS are square wave signals, and a timing diagram is shown in FIG. 4.

An embodiment of the present disclosure further provides a data drive device including a data drive unit and a drive compensation circuit. The data drive unit is electrically coupled to the drive compensation circuit. The data drive unit is electrically coupled to data lines. The drive compensation circuit is described as above.

In summary, although the present disclosure has been provided in the preferred embodiments described above, the foregoing preferred embodiments are not intended to limit the present invention. Those skilled in the art, without departing from the spirit and scope of the present invention, may make modifications and variations, so the scope of the protection of the present disclosure is defined by the claims.

What is claimed is:

1. A drive compensation circuit, comprising a first register unit, a second register unit, a selection unit, a voltage level shifter, a digital-to-analog conversion unit, and an amplification unit;

wherein the first register unit and the second register unit are respectively connected to the selection unit, and the selection unit, the voltage level shifter, the digital-to-analog conversion unit, and the amplification unit are connected in sequence;

the first register unit is configured to acquire and store a first compensation signal;

the second register unit is configured to acquire and store a second compensation signal;

the selection unit is configured to selectively connect the first register unit or the second register unit to the voltage level shifter, the voltage level shifter processes and transmits the first compensation signal or the second compensation signal to the digital-to-analog conversion unit, the digital-to-analog conversion unit converts the processed first compensation signal or the processed second compensation signal to a corresponding analog signal, and the amplification unit amplifies the analog signal with a predetermined multiple and then transmits the amplified analog signal to a data drive circuit for compensation;

the amplification unit is an analog buffer amplifier, and the selection unit is a switch chip.

2. The drive compensation circuit of claim 1, wherein the first register unit comprises a first receiver, a first shift register, and a first data register, and the first receiver, the first shift register, and the first data register are connected in sequence.

3. The drive compensation circuit of claim 2, wherein the second register unit comprises a second receiver, a second shift register, and a second data register, and the second receiver, the second shift register, and the second data register are connected in sequence.

4. The drive compensation circuit of claim 3, wherein the first receiver and the second receiver are Mini-LVDS receivers.

5. The drive compensation circuit of claim 3, further comprising a frame memory, and the frame memory storing the first compensation signal and the second compensation signal.

6. The drive compensation circuit of claim 5, wherein the first data register has a first control port configured to access a first control signal STB1, the second data register has a second control port configured to access a second control signal STB2, and the selection unit has a third control port configured to access a third control signal DS;

when the third control signal DS is at a low level, the first compensation signal in the frame memory is read and stored in the first shift register; when the first control signal STB1 is at a rising edge, the first compensation signal is outputted to the first data register;

when the third control signal DS is at a high level and the first control signal STB1 is at a falling edge, the first compensation signal in the first data register is transmitted to data lines after being processed by the voltage level shifter, the digital-to-analog conversion unit, and the amplification unit;

when the second control signal STB2 is at a rising edge, the second compensation signal is stored in the second data register; when the third control signal DS is at a low level and the second control signal STB2 is at a falling edge, the second compensation is transmitted to the data lines.

7. A drive compensation circuit, comprising a first register unit, a second register unit, a selection unit, a voltage level shifter, a digital-to-analog conversion unit, and an amplification unit;

wherein the first register unit and the second register unit are respectively connected to the selection unit, and the selection unit, the voltage level shifter, the digital-to-analog conversion unit, and the amplification unit are connected in sequence;

the first register unit is configured to acquire and store a first compensation signal;

the second register unit is configured to acquire and store a second compensation signal;

the selection unit is configured to selectively connect the first register unit or the second register unit to the voltage level shifter, the voltage level shifter processes and transmits the first compensation signal or the second compensation signal to the digital-to-analog conversion unit, the digital-to-analog conversion unit converts the processed first compensation signal or the processed second compensation signal to a corresponding analog signal, and the amplification unit amplifies the analog signal with a predetermined multiple and then transmits the amplified analog signal to a data drive circuit for compensation.

8. The drive compensation circuit of claim 7, wherein the first register unit comprises a first receiver, a first shift register, and a first data register, and the first receiver, the first shift register, and the first data register are connected in sequence.

9. The drive compensation circuit of claim 8, wherein the second register unit comprises a second receiver, a second shift register, and a second data register, and the second receiver, the second shift register, and the second data register are connected in sequence.

10. The drive compensation circuit of claim 9, wherein the first receiver and the second receiver are Mini-LVDS receivers.

11. The drive compensation circuit of claim 9, further comprising a frame memory, and the frame memory storing the first compensation signal and the second compensation signal.

12. The drive compensation circuit of claim 11, wherein the first data register has a first control port configured to access a first control signal STB1, the second data register has a second control port configured to access a second control signal STB2, and the selection unit has a third control port configured to access a third control signal DS;

when the third control signal DS is at a low level, the first compensation signal in the frame memory is read and stored in the first shift register; when the first control signal STB1 is at a rising edge, the first compensation signal is outputted to the first data register;

when the third control signal DS is at a high level and the first control signal STB1 is at a falling edge, the first compensation signal in the first data register is transmitted to data lines after being processed by the voltage level shifter, the digital-to-analog conversion unit, and the amplification unit;

when the second control signal STB2 is at a rising edge, the second compensation signal is stored in the second data register; when the third control signal DS is at a low level and the second control signal STB2 is at a falling edge, the second compensation is transmitted to the data lines.

13. A data drive device, comprising a data drive unit and a drive compensation circuit, and the data drive unit and the drive compensation circuit are connected to data lines,

wherein the drive compensation circuit comprises a first register unit, a second register unit, a selection unit, a voltage level shifter, a digital-to-analog conversion unit, and an amplification unit;

the first register unit and the second register unit are respectively connected to the selection unit, and the selection unit, the voltage level shifter, the digital-to-analog conversion unit, and the amplification unit are connected in sequence;

the first register unit is configured to acquire and store a first compensation signal;

the second register unit is configured to acquire and store a second compensation signal;

the selection unit is configured to selectively connect the first register unit or the second register unit to the voltage level shifter, the voltage level shifter processes and transmits the first compensation signal or the second compensation signal to the digital-to-analog conversion unit, the digital-to-analog conversion unit converts the processed first compensation signal or the processed second compensation signal to a corresponding analog signal, and the amplification unit amplifies the analog signal with a predetermined multiple and then transmits the amplified analog signal to a data drive circuit for compensation.

14. The data drive device of claim 13, wherein the first register unit comprises a first receiver, a first shift register, and a first data register, and the first receiver, the first shift register, and the first data register are connected in sequence.

15. The data drive device of claim 14, wherein the second register unit comprises a second receiver, a second shift register, and a second data register, and the second receiver, the second shift register, and the second data register are connected in sequence.

16. The data drive device of claim 15, wherein the first receiver and the second receiver are Mini-LVDS receivers.

17. The data drive device of claim 15, further comprising a frame memory, and the frame memory storing the first compensation signal and the second compensation signal.

18. The data drive device of claim 17, wherein the first data register has a first control port configured to access a first control signal STB1, the second data register has a second control port configured to access a second control signal STB2, and the selection unit has a third control port configured to access a third control signal DS;

when the third control signal DS is at a low level, the first 10

compensation signal in the frame memory is read and stored in the first shift register; when the first control signal STB1 is at a rising edge, the first compensation signal is outputted to the first data register;

when the third control signal DS is at a high level and the 15

first control signal STB1 is at a falling edge, the first compensation signal in the first data register is transmitted to data lines after being processed by the voltage level shifter, the digital-to-analog conversion unit, and the amplification unit;

20

when the second control signal STB2 is at a rising edge, the second compensation signal is stored in the second data register; when the third control signal DS is at a low level and the second control signal STB2 is at a falling edge, the second compensation is transmitted to 25 the data lines.
